BENJAMIN L. DENNISON, OF BOSTON, MASSACHUSETTS.

Letters Patent No. 83,368, dated October 27, 1868.

IMPROVEMENT IN ATTACHING STRINGS TO TAGS.

The Schedule referred to in these Letters Patent and making part of the same.

To whom it may concern:

Be it known that I, BENJAMIN L. DENNISON, of Boston, in the county of Suffolk, and State of Massachusetts, have invented a new and improved Method of Attaching Strings to Label-Cards and Merchandise-Tags; and I do hereby declare the following to be a full and exact description thereof; reference being had to the accompanying drawings, and to the letters of reference marked thereon, in which—

Figure 1 shows the tag and string, with clasp applied at the ends of the string.

Figure 2 shows the card and string, with the pointed clasp applied at the ends of the string.

Figure 3 shows the card and string, with the clasp applied near the card.

Figure 4 is a section of the clasp.

Figure 5 is an under-side view of the pointed clasp.

The nature of my invention consists in using a metallic clasp for fastening the strings to the label-cards or tags, so that they may be strung and fastened by machinery.

To enable others skilled in the art to make and use my invention, I will proceed to describe its construction and operation.

I take any label-card or tag, having an eyelet or perforation through it, and passing a string through it, and, bringing together the two strands, fasten them with a metallic clasp by means of any suitable machinery.

The clasp may be applied at the ends of the string,

as in figs. 1 and 2, or near the card or tag, as in fig. 3.

The clasp *a*, figs. 2 and 5, is made by cutting away or bending down the lips of one end, to the centre of the clasp, to a point, before applying it to the string, and then clasping the lips of the other end over the ends of the string, so that the pointed end will be directed towards the label. By running the point of the clasp so attached through the cloth or other textile fabric, and drawing the clasp and part of the string through, and then drawing back the string, the clasp assumes the position shown in fig. 2, and acts as a bar to prevent it from drawing out.

The object of my invention is to furnish, in a cheap and convenient manner, label-cards or tags, provided with strings suitable for attaching them to merchandise, and so fastening the string to the tag, by machinery or otherwise, that it will not drop out.

What I claim as my invention, and desire to secure by Letters Patent, is—

1. The combination of the metallic clasp *a* with the string and label-card, substantially as and for the purposes described.

2. The metallic clasp *a*, figs. 2 and 5, constructed so as to operate as a clasp, a needle, and a bar, at the same time, substantially as and for the purposes described.
